UNITED STATES PATENT OFFICE.

JONAS G. LUNDGREEN, OF CLEAR LAKE, IOWA.

COMBINED ELECTRIC SWITCH AND FUSE.

Application filed January 26, 1921. Serial No. 449,005.

To all whom it may concern:

Be it known that I, JONAS GUSTAF LUNDGREEN, citizen of the United States, residing at Clear Lake, in the county of Cerro Gordo 5 and State of Iowa, have invented new and useful Improvements in Combined Electric Switches and Fuses, of which the following is a specification.

My invention relates to a combined fuse 10 and switch construction.

In many electrical installations the fuse is exposed to view with the result that when the fusible element has burned out there is a temptation, which is frequently yielded to especially if there is no supply of the proper fusible elements on hand, to put a copper wire or some like form of conductor in the place of the fuse. This procedure, as is well known to those skilled in the art to 15 which this invention appertains, frequently leads to serious trouble which would not occur if the fusible element had been in place and capable of performing its function. Furthermore, the service switch is frequently placed in exposed places where children 20 or unauthorized persons may come in contact with the terminals with resulting serious consequences.

This invention aims to avoid these and 25 other difficulties and also to provide a compact arrangement whereby the fuse and switch are combined in a unitary structure wherein the fuse is not exposed to view and wherein the terminals of the switch are also 30 concealed.

This invention also aims to provide a fuse construction which may be readily assembled and disassembled for inspecting or replacing the fusible element.

Another object of my invention is to provide a combined fuse and switch-block so arranged that the conductors may be firmly and readily connected thereto.

Other objects of the invention which consist in novel features of construction and arrangements of parts whereby a compact and economical structure is obtained, will become apparent on reference to the following specification which describes the invention 45 in connection with the accompanying drawings.

In the drawings:—

Figure 1 is a plan view of one form of my invention showing a plurality of terminals disposed on a switch-block.

Figure 2 is a central sectional view

through one of the detachable switch and fuse devices, on the line 2—2 of Figure 1.

Figure 3 is a transverse section on the line 3—3 of Figure 1, looking in the direction of the arrows and with other parts broken away.

Figure 4 is a perspective view of a fuse cartridge showing one of the end covers removed.

Figure 5 is a perspective view showing the parts comprising the detachable cap and screw of the switch mechanism in separated position.

Figure 6 is a plan view of another form of 70 my invention showing the switch elements pivotally connected.

Figure 7 is a central longitudinal section through one of the switch elements.

Figure 8 is an end view of the switch 75 in closed position showing one of the switch elements in section on the line 8—8 of Figure 7.

Figure 9 is a vertical section through one 80 of the terminal connections to the switch-block, the section being taken on the line 9—9 of Figure 7.

Referring to the form of the invention illustrated in Figures 1 to 5, the numeral 10 designates the switch-block which is prefer-

ably of substantially rectangular shape and formed of some insulating material such as porcelain or bakelite. This block is formed with transverse grooves which are adapted to receive the insulated conductors 12. These

grooves are intersected near opposite sides of the block by slots 13, in which are located the switch blades consisting of flat elongated base portions 14 disposed in the bottom of the slots and secured to the block 90 by means of suitable screws or other fastening devices (not shown). Upstanding from the bases 14 are the blades 15 which are adapted to cooperate with the spring

fingers 33 of the detachable switch and fuse 100 mechanism. Each base portion 14 is extended into a groove 11 and is provided with apertures and screw threads which apertures are spaced apart a sufficient distance for the bare wire to pass therethrough,

so that at this point the insulation is cut away from the wire, and a metallic plate 16 of proper dimension having suitably spaced apertures is used to clamp the wire 105 firmly in position and make good electrical contact therewith and for this purpose the

screws 17 are passed through the apertures

of the plate 16 and engage the threaded apertures of the plate 14. Recesses 20 are formed near each corner of the block and in axial alignment with the slots 13. Means are provided in each of the recesses for electrically connecting the terminals of an electrical conductor to a terminal of the switch block and this means comprises a metallic plate 21 located in the base of each recess and properly secured to the block 10 and another metallic plate 22, between which plates the uninsulated portion 23 of the conductor is inserted, the insulation shown at 24 being received through a vertical slot of proper dimension formed in the switch block.

The base-plate 21 is provided with apertures and screw threads and the upper plate 22 has suitable apertures for receiving the screws 25 whereby the two plates may firmly bind the uninsulated portion 23 of the conductor between them. A blade 26 is attached to or formed integral with the upper plate 22 and is adapted to cooperate with the spring fingers 33 of a detachable combined switch and fuse device as will hereinafter appear. As shown in Figure 1, there are four switch blades 26 arranged near the corners of the rectangular switch-block and two switch blades 15 which latter are connected with the transversely extending conductors 12.

The combined fuse and switch devices are provided so that pairs of these blades 15 and 26 may be variously connected in accordance with conditions. These combined switch and fuse mechanisms are designated as a whole by the numeral 30 and each consists of a cylindrical, hollow casing 31 of insulating material in each end of which is inserted or embedded a threaded metallic bushing 32 and this bushing is provided with spring fingers 33 adapted to engage and make contact with the switch blades 15 and 26 in the usual manner. The bushing may be attached to the casing in any suitable manner. The outer end of each pin or rivet projects into an opening formed in the casing and this opening is subsequently filled by a plug 29 of wood, wax, putty or the like so that the outer surface of the casing is continuous and of even contour, as shown in Figure 2.

The fuse is of novel construction in order that the same may be readily disassembled and assembled, and for this purpose a cylindrical fuse body 34 of insulating material and of such dimension as to be capable of fitting within the hollow casing 31, is provided. The fuse body is formed with central bore 36 and with recessed ends 37 in each of which recesses a circular metallic disk 38 having spaced apertures therein is adapted to fit. A fusible element 39 extends through the central bore 36 through

one set of aligning apertures in the opposite disks 38 and is then bent over so that the ends may be inserted through the other set of apertures in the disks 38 thus exposing on the faces of the disks 38, flat portions 40 adapted to contact with metallic caps 41. Each metallic cap 41 is provided with an annular flange 42 from which project lugs 43 having inturned ends 44 for engaging in slots 45 and grooves 46 which cooperate with the flanges 43 in providing a bayonet joint adapted to connect the cap to the fuse body. It will be noted that in Figure 4 the upper surface of the groove 46 is shown as provided with a slight taper indicated at 47 so that the cap may be pressed into firm electrical contact with the corresponding end 40 of the fuse 11. However, it will be noted that a straight surface may also be used in connection with the groove 46 of the bayonet joint since the screw-plugs 48, hereinafter described, will force the caps 41 firmly into contact with the flat portions 40 of the fusible element. The fuse body shown in Figure 4 is adapted to be inserted within the switch-block or casing 31 and the metallic caps 41 thereof extend within the threaded portions of the bushings 32. In order to make certain of good electrical connections between the bushings 32 and the fuse, a nut or screw-plug 48 of metallic material, such as brass, is provided with threads for engaging the threads of each bushing 32 and by inserting these screw-plugs in the opposite ends of the casing 31, the fuse is firmly held therebetween. Each screw 48 is also provided with a central threaded aperture 49 and with a kerf 50 adapted to engage a screw-driver whereby the plug 49 may be easily detached. For the purpose of concealing the conducting parts of the apparatus and preventing accidental contact therewith, a cap 51 of non-conducting material is formed with a slotted boss 52, the slot of which is adapted to engage the head of a T-shaped element 53 having a threaded stem 54 adapted to engage the threads 49 of the screw-plug. The T-shaped element is provided with an aperture 55 which is adapted to align with an aperture 56 passing transversely through the hub 52, whereby a removable pin or wire may be inserted for retaining the cap 51 and the T-shaped element 53 in assembled relation. By removing the pin from the apertures 55 and 56 and placing the stem 54 in the central aperture 54a of the cap 51, the T-shaped element will be positioned for engaging the kerf 50, and thereby functioning as a screw-driver with relation to the plug 48, or the T-shaped element may be used as a screw-driver independently of the cap 51.

In assembling the detachable switch and fuse mechanism, the assembled fuse is inserted within the casing 31, screw plugs 48

are applied and the caps 51 are secured to these plugs, whereby the device presents a neat appearance and exposes only the insulating material of the casing 31 and caps 51 to view, with the exception of the switch blades 33, which extend downwardly through slots in the casing. As said before, these combined switch and fuse devices connect the switch blades 15 and 26, and 5 since the latter are located in slots in the switch block 10 and the block is provided with cylindrical depressions 57 of substantially the same or slightly larger diameter than the casings 31 it will be apparent that 10 15 when the switch devices are applied in closed position that the conducting terminals are protected from accidental contact therewith by a person not acquainted with the construction of the switch mechanism and 20 25 that anyone accidentally coming into contact therewith is in little danger of being subjected to an electrical shock.

In case the fuse is burnt out, or is defective, or in order to inspect; remove the cap 51, the plug 48 and shake out the fuse body 34, the caps 41 can then be readily detached and the disks 38 removed. Under these conditions the interior of the switch block is exposed to view, as well as the fuse element and if it is desired to put another fuse element in place it is only necessary to insert the same through the apertures of the disks 38, after removing the spent fuse, as above described. The switch block 10 is provided 30 35 with openings 58 for receiving suitable means for fastening the switch mechanism to a wall or switch board slab.

Another form of my invention, illustrated in Figures 6 to 9, differs from the form just 40 45 described chiefly in having the switch members pivotally mounted instead of completely removable and this form is primarily intended for a main or service switch. The switch mechanism is mounted upon a block 60 having two forward recesses 61 and two rear recesses 62 formed therein. In each of the rear recesses 62 a base plate 63 is placed, see Figure 9, on which is mounted a bent plate 65 having an upstanding blade 50 55 portion 66 to which the hollow cylindrical casing 67 of the movable switch member is pivotally connected in a manner hereinafter described. The rear end of each casing 67 is closed by a metallic plug 68 having spaced 60 65 fingers 69 extending therefrom for embracing the upstanding blade 66 of the bent plate 65. A pin 70 is passed through aligning apertures formed in the blade 66 and fingers 69, this pin being retained in position by suitable retainers such as washers 71 and the riveted ends of the pin 70 which prevent lateral movement of the washers. It will be understood that other retaining means such as cotter pins or screws and nuts or the like 65 70 75 80 85 90 95 100 105 110 115 120 125 130 may be used instead of the means herein em-

ployed. In order to allow pivotal movement of the casings 67 about the blades 66 said casings are provided with vertical slots 72 which provide clearance for the blades 66 during pivotal movements of the casings. 70

In the forward recesses 61 a base plate 75 is inserted and upon this plate is placed an elongated plate 76. The plate 75 is provided with a curved portion 77 which is produced upwardly into the vertical blade 78. The 75 plates 75 and 76 are secured to the switch block 60 by suitable fastening devices (not shown) and the plate 75 is provided with apertures adapted to align with suitable apertures formed in a plate 80 which engages 80 over the uninsulated portion of the wire 81 for tightly clamping the wire into electrical contact with the plate 76 and for this purpose screws 82 are inserted through the aligning apertures and the plate is pressed 85 downwardly until the wire is tightly clamped between the plate 80 and the plate 76. The wires 83 leading into the rear recesses are secured in place in similar manner by means of the upper contact plate 84 90 which is provided with apertures through which screws 85 are inserted for the purpose of engaging threaded apertures in the plate 63, suitable openings being made in the block 60 to allow the screws to be tightened. 95

Each hollow cylindrical casing 67 is closed at one end by the metallic plug 68, and a fuse 86, similar in construction to the fuse described in connection with the first form of my invention is inserted within each casing until the metallic cap 87 of one end of the fuse is received within and contacts with the shell of the plug 68. The cap 87 at the other end of the fuse body is received within a threaded bushing 32' having depending spaced fingers 33' for engaging the blade 78 of the forward terminals of the switch mechanism. A screw plug 48' screws into the bushing 32' and contacts with the corresponding metallic cap 87. A cap 51' of insulating material is provided with a threaded stem 54' adapted to engage a central threaded aperture in the screw plug 48'. The primed numerals represent parts corresponding in construction and function to the parts designated by the corresponding cardinal numerals in the description of Figures 1 to 5. 110 115

The two cylindrical casings 67 are connected together at the forward end by a bridge piece 90 having inwardly projecting ribs 91 secured to the casings. The bridge piece 90 is provided with a circular opening 92 whereby the movable switch members including the casings 67 may be readily manipulated to open or closed position. 120 125

When the switch is in closed position the current coming through conductors 81 is transmitted by means of spring fingers 33' to threaded bushings 32', from thence to 130

screw plug 48', cap 87 through the fusible element 39, which is substantially the same in each form of the invention herein described, to the rear cap 87, through shell 68, 5 fingers 69, to blade 66 and then to conductor 83. It is evident that the blowing of the fuse will break this line of conductors and the fuse may be replaced by swinging the casings to open position, taking out the 10 movable parts 51', 48', 87 and the fuse as described in connection with the corresponding parts of the first form of the invention, inserting the new fuse and assembling the parts in reverse order.

15 The cylindrical openings at the rear of the casings surrounding the spring fingers 69 are closed by means of plugs 88 of insulating material which conform exteriorly to the contour of the casings and except for 20 the continuation of the slots 72 completely conceal the switch blades 66 and spring fingers 69.

The block 60 is also formed with curved longitudinal depressions 89 adapted to receive 25 the lower portions of the casings when the latter are closed and thus conceal the conducting portions of the switch mechanism in a housing of insulating material.

It will be understood that the particular 30 constructions described and shown have been chosen for illustrative purposes merely and that the invention as defined by the claims hereunto appended, may be otherwise embodied and applied without departing from 35 the spirit and scope thereof.

Having described my invention what I claim and desire to secure by Letters Patent, is:—

1. In an electrical switch, the combination 40 of a switch block having spaced terminals, a casing carrying contacts adapted to make electrical connections with said terminals, a fuse in said casing connecting said contacts, said block having recesses in which 45 said terminals are located and grooves there-

in which portions of said casings are adapted to fit, and detachable means for closing an end of said casing whereby when the switch is closed all of the conducting parts thereof are concealed from view. 50

2. An electrical switch having in combination a movable member consisting of a hollow casing, spaced contacts in said casings and a fuse comprising a hollow body, metallic caps detachably connected to said body, a fuse element electrically connecting said caps, and a removable plug engaging one of said contacts for forcing said contacts, caps and fuse element into firm electrical contact. 55

3. In an electric switch the combination of a fixed block of insulating material having recesses formed therein, terminals located in said recesses, a casing of insulating material having contacts projecting therefrom adapted to engage said terminals, a fuse within the casing electrically connecting said contacts, said block having grooves formed therein in alignment with said recesses for receiving said casing when the latter is in operative position, whereby the coacting terminals and contacts are completely housed by said block and casing. 60

4. An electrical switch including a member consisting of a hollow casing of insulating material having spaced contacts, a fuse within the casing, a removable metallic plug engaging one of said contacts for making firm electrical connections between said contacts and fuse, a cap of non-conducting material adapted to act as insulator for said plug, and a disassembling tool detachably connecting said cap and plug. 65

In testimony whereof I have hereunto set my hand in presence of two subscribing witnesses. 85

JONAS G. LUNDGREN.
